UNITED STATES PATENT OFFICE.

CHESTER E. CLEMENS, OF CLEVELAND, OHIO.

LEVER-LOCKING DEVICE.

1,190,517.

Specification of Letters Patent. Patented July 11, 1916.

Application filed June 5, 1913. Serial No. 771,809.

To all whom it may concern:

Be it known that I, CHESTER E. CLEMENS, a citizen of the United States, residing at Cleveland, in the county of Cuyahoga and 5 State of Ohio, have invented a certain new and useful Improvement in Lever-Locking Devices, of which the following is a full, clear, and exact description, reference being had to the accompanying drawings.

10 This invention relates generally to locks, and particularly to locks for preventing the movement of the gear shifting levers of automobiles from ineffective or "dead" position; and it has for its objects the provision 15 of a lock of this character which is very substantial; simple of construction; economical of production; convenient of operation; and one which can be easily applied to levers of the type with which it is adapted to 20 be used.

The essence of the invention may be best expressed by stating that the lock involves two principal members (one of which is required to be, and the other of which may 25 be, cylindrical) which are disposed at right angles toward each other, one being capable of rotation and the other of reciprocation, the zones of the members slightly intersecting. To permit of such construction, I provide each member with a notch which is equal 30 in depth to the extent of the aforesaid intersection and of a shape corresponding to the contour of the other member, the notches being effective, alternately. When the notch 35 in the rotating member embraces the other member, the latter is permitted to reciprocate, and when the notch in the reciprocating member embraces the curved surface of the rotating member, the former is effectively locked against reciprocation. With 40 this principle in mind, I will proceed to consider the embodiments of the invention illustrated in the accompanying drawings, wherein—

45 Figure 1 is a side elevation of the gear shifting lever of an automobile having the lock of my invention applied thereto, the sector or gate within which said lever is guided, being shown in section; Fig. 2 is a 50 front elevation, on a considerably larger scale, of what is shown in Fig. 1, the lock and the sector or gate being shown in section; Figs. 3 and 4 are central vertical sections through the lock, showing the lock attached to a lever as in the preceding figures, the former of said figures showing the parts

in unlocked position, as in Fig. 1, and the latter the parts in locked position as in Fig. 2 (the last two figures being on the same scale as Fig. 2); Fig. 5 is a side elevation 60 of the body portion of my lock with the cover which normally closes the end of the auxiliary lock removed; and Fig. 6 is a sectional detail on line 6—6 of Fig. 5 and looking in the direction of the arrows, (the 65 scale being further increased in Figs. 5 and 6 for clearness); Fig. 7 is a view similar to Fig. 1 and showing a modified form of my invention; Figs. 8 and 9 are sectional details corresponding to line 8—8 and 9—9 of Fig. 7; and Figs. 10 and 11 are a plan and side elevation, respectively, of a further modification of my lock.

Like reference characters designate corresponding parts throughout the several views 75 of the drawings.

Referring to that form of my invention illustrated in Figs. 1 to 6, 1 represents the gear shifting lever of an automobile and 2 the sector or gate which has a slot 3 wherein 80 the lever is guided in its movements. As is well known, the slot 3 in the sector or gate 2 is H-shaped, and when the lever occupies that portion of the slot which corresponds to the cross of the H, or is in the general 85 vicinity of such portion, the lever is in inoperative or "dead" position. When the lever occupies either end of either of the branches of the slot, the gears which are controlled thereby are in mesh. Secured to 90 the lever 1 a slight distance above the sector or gate 2 is a block 4 which is substantially U shape in plan and which I will refer to hereinafter as the body portion of my lock. The legs of this U block or body portion 95 embrace the lever 1 and are secured thereto by a rivet 5 which passes through said legs and through the lever 1. Immediately forward of the lever 1, the body portion 4 is provided with a vertical cylindrical 100 bore 6 within which is adapted to reciprocate the rod or bolt 7. Extending transversely of the body portion 4 and at right angles to the aforesaid bore, is a second cylindrical bore 8 for the reception of the 105 barrel 9 of an ordinary Yale lock, the said bores 6 and 8 slightly intersecting, as will be seen clearly upon referring to Figs. 2, 4 and 6. A notch 10 is formed in the side of the bolt 7 and is curved on a radius corresponding to the radius of the barrel 9; and the barrel 9 is provided with a transverse 110

curved notch 11 of a radius equal to that of the rod 7. The upper end of the bolt 7 is provided with a head 12 and at its lower end it carries a block 13 which extends from beneath the body portion 4 along one side of the lever 1 where it terminates in a depending lug 14. The side of the bolt 7 which is presented to the barrel 9 is provided with a second notch 15 for a purpose which will be mentioned later, and extending from the opposite side of the rod a slight distance above the notch 15 is a pin 16 which is adapted to travel within a key-way or channel 17 extending along one side of the bore 6 and which acts to prevent any angular movement of the bolt 7. The upper end of the bore 6 is counterbored for the reception of a spring 18 which surrounds the rod 7 and is confined between the underneath surface 20 of its head 12 and the bottom of the aforesaid counterbore. This spring acts to retain the bolt 7 with its block 13 and lug 14 in elevated position. Holes, which extend through the body portion 4 from its top to 25 where they communicate with the bore 8, directly above its center, contain small cylindrical plungers 19 which are depressed by springs 20, the springs being confined within the holes by a plate 21 which occupies a horizontal channel in the front face of the body portion 4 near its upper edge. After the plate 21 is inserted in the channel, the overhanging lip of the body portion 4 is pressed downwardly to effectively clamp the plate in position. The plungers 19 are adapted to 30 coöperate with the tumblers 22 of the Yale lock and be elevated thereby against the tension of the springs 20 when the key is inserted in said lock. The elevation of the plungers thus effected by the insertion of the key is sufficient to bring the dividing line between the plungers and the tumblers coincident with the surface of the barrel 9 to permit said barrel to be rotated by the key. 35 As will be seen most clearly from Figs. 5 and 6 the barrel 9 of the Yale lock is provided at one end with a flange 23 which bears against that part of the surface of the body portion which surrounds the bore 8, and the opposite end of the barrel is reduced to form a substantially cylindrical boss 24 which is flattened on one side to prevent any relative movement between the barrel and the disk or washer 25 which is mounted upon 40 the aforesaid boss and which has a hole within its center for the reception of said boss and which is of substantially the same shape as said boss. From Fig. 6, it will be seen that the disk or washer 25 is of greater diameter than the barrel 9 and, to accommodate the washer, the side of the body portion 4 is provided with a circular recess 26 which is concentric with the bore 8 and is of slightly greater diameter than the disk 25. 45 A segmental notch 27 is formed in the

periphery of the disk 25 and extends through substantially 90° of its circumference. A pin 28, which projects from the bottom wall of the recess 26 occupies the notch 27 and is adapted to abut against the ends of the notch to limit the extent of the rotation of the barrel 9 in either direction. A coil spring 29 is anchored at one end to the pin 28 and at its opposite end is attached to the disk or washer 25 in any suitable manner, as by having the end turned over and inserted into a hole in said disk or washer, as shown. This spring, through the intervention of the disk or washer 25, tends to rotate the barrel 9 in a direction to bring into register the holes which contain the tumblers 22 and those containing the plungers 19 which are formed in the body portion of the lock, and the accurate alinement of these holes is insured by the stop provided by the pin 28 and the end of the notch 27. To conceal the parts just described and to produce a smooth and finished appearance to that side of the lock which contains the recess 26, I provide a cap 30 having an annular flange 31 of a diameter substantially equal to the diameter of the said recess. After the parts are assembled, I press this cap firmly into the recess where it is effectively retained by friction. 95

To actuate my lock the operator presses downwardly on the head 12 of the bolt 7 against the action of the spring 18 until the notch 10 in the rod is in register with the bore 8 and forms, in effect, a continuation of the wall thereof. Through the influence of the spring 29, the barrel 9 of the Yale lock will then be rotated to bring the holes containing the tumblers 22 and those containing the plungers 19 into alinement, when the plungers will be forced downwardly by the springs 20 and into the holes of the bore in the barrel 9, which securely locks the barrel against rotation. With the bolt 7 in this depressed position, the lug 14 of the block 110 13 rests in the slot 3 and protects the lever 1 against effective operation. To release the lock, it is only necessary to insert an appropriate key into the lock, as shown in Fig. 2, when the plungers 17 will be ejected from 115 the lock as previously described, and permit of a quarter rotation of the barrel of the lock. Upon such movement, the notch 11 in the barrel 9 is brought into alinement with the vertical bore 6, and permits the elevation of the rod 7 by the spring 17. 120

The form of my lock thus far described is adapted to be located in proximity to the sector or gate 2, where it performs the function of a lock only. The form of my invention which I will now describe and which is illustrated in Figs. 7 to 9, inclusive, acts not only as lock for the gear shifting lever, but also as a safety device to prevent the driver from inadvertently throwing the le- 130

ver into that branch of the slot within the sector or gate which represents "reverse." Serious accidents have occurred because of such mistake, and means for preventing its occurrence is valuable and very desirable. In this form of my invention, the body portion 4 and the parts included in it are the same as previously described, and it is secured to the lever 1 in precisely the same manner, except that it is located directly beneath the grip of said lever. The bolt or rod 7^a, however, is capable of movement in either direction from its normal position, and is centrally located by a pair of opposed springs 32 and 33, the former of which corresponds to the spring 17 in the previous embodiment. The spring 32 is confined between the upper surface of the body portion 4 of the lock and a flange 34 which is carried by the head 35 of the bolt or rod and the spring 33 is interposed between the bottom surface of the body portion 4 and a collar 36 which is carried by the rod 7^a. Below this collar, the bolt or rod is reduced in size and extends to within a short distance of the sector or gate 2 and has secured to its lower end a slide 37, by means of a projection 38, which is of general U shape and which embraces the edge of the lever 1. The slide 37 is movably attached to the side of the lever 1 by a rivet 39 which passes through the lever and through a bushing 40 which is confined between the head of the rivet and the surface of the lever 1. The outer end of the bushing overhangs the edge of a slot 41 in the slide 37 and forms a spacer for the rivet 39 to prevent its binding the slide 37 against the lever. This forms a cheap and convenient method of attaching the slide to the lever, and insures freedom of movement. When the parts are in normal position, or that shown in Fig. 7, the lever 1 is free to move into any branch of the H-shaped slot 3 within the sector or gate 2 except the one which represents the reverse for the automobile and which I have designated 3^a in Fig. 8, the entrance of the lever into this portion of the slot being ordinarily prevented by the engagement of the lower portion of the slide 37 with the projection 2^a on the sector or gate. When it is desired to reverse the automobile, the slide 37 is elevated above the projection 2^a by pulling upwardly on the rod 7^a, when the slide may pass over the top of said projection. To expedite this operation I make the head of the rod 7^a in the form of a ring into which the operator may insert his finger. After the initial movement of the lever in "reverse" direction, the parts may be released, allowing the slide 37 to resume its normal position, the slide being automatically elevated when returning to central position by its engagement with the rear, inclined side of the projection 2^a. To

lock the lever against any movement other than a slight lateral shifting, the rod 7^a is depressed as in the former case to project the lower end of the slide 37 into the slot 3, in which position the parts are held by the coöperation of the Yale lock and the notch within the rod 7^a.

Figs. 10 and 11 illustrate a form of my invention wherein the lever 1^a forms one of the principal members of my lock, while the body portion 42, which contains the Yale lock, is movable. As will be seen from Fig. 10, the body portion 42 is of general U shape in plan and embraces the forward edge of the lever 1^a, and it is secured to said lever by a rivet 43 which passes through a slot in one side of the U-shaped body portion 42 and through a hole in the lever. Between the head of the rivet 43 and the adjacent side of the lever 1^a, the body portion 42 is enlarged to form a vertically disposed boss which is made hollow for the reception of a compression spring 44 that is adapted to bear against the upper wall of the hollow boss and the rivet 43. This spring tends to elevate the body portion 42 and withdraw its enlarged lower end 45 from the slot in the gate or sector 2. To assist the rivet 43 in accurately guiding the body portion 42, I provide a pin 46 which extends through the lever 1^a and projects at either end into vertical grooves on the inner walls of the legs of the U-shaped body portion 42. A notch 47 in the edge of the lever 1^a cooperates with the barrel of the lock to retain the parts in locked position when the body portion 42 is depressed, in the same manner as the notches in the rods 7 and 7^a.

The notch 15, to which reference has been made hereinbefore, permits of the removal of the key after the barrel 8 has been turned to the position shown in Fig. 3.

Having thus described my invention, what I claim is:

1. The combination, with a sector and a lever movable relatively thereto, of a member slidably supported by said lever and adapted to engage the sector to prevent movement of the lever with respect thereto, means tending to move said member away from the sector, said member having a notch or recess, a lock comprising a rotary barrel which is intersected by said member and is notched to permit the movement of the same, the unrecessed portion of the barrel being adapted to enter the notch and retain the member in sector-engaging position, and means for rotating the barrel.

2. The combination, with a sector and a lever movable relatively thereto, of a member slidably mounted on said lever and adapted to engage the sector to prevent movement of the lever with respect thereto, a spring tending to move said member away from the sector, said member having a bolt

provided with a recess, a lock comprising a rotary barrel which is intersected by said bolt and is recessed to prevent the movement of said bolt, the unrecessed portion of the 5 barrel being adapted to enter the bolt notch and retain the bolt in sector-engaging position, and a spring tending to rotate the barrel.

3. The combination, with a sector and a 10 lever movable relatively thereto, of a member slidably mounted with respect to the lever and adapted to engage the sector to prevent movement of the lever, means normally holding said member out of engagement with the sector, a rotary cylindrical barrel, a bolt carried by the member, the cylindrical barrel being arranged at substantially right angles to and intersecting the path of movement of the bolt and having a notch or recess in a portion thereof to permit the movement of the bolt when said recess is in register with said bolt and the bolt having a cylindrical recess adapted to receive the cylindrical body of the barrel when the member is in sector-engaging position, a spring tending to rotate the barrel into bolt-engaging position, and key operated means for rotating the barrel to bring its notch into register with the bolt.

4. The combination, with a sector and a lever movable relatively thereto, of a casing mounted on said lever, said casing having a guideway and a cylindrical bore, at right angles to and intersecting each other, a bolt reciprocably mounted in the said guideway, and having an extension adapted to engage the sector, a spring surrounding the bolt and tending to hold the said extension out of engagement with the sector, a lock barrel rotatably mounted in said bore and having a portion thereof provided with a notch or recess for the adjacent surface of the bolt and said bolt having a cylindrical recess in the portion thereof which is 45 presented toward the barrel and which is adapted to receive the said barrel to thereby lock the said bolt and extension in sector-engaging position, a spring adapted to rotate the barrel when the notch or recess in the bolt is in register with the cylindrical bore, means for locking the barrel in bolt-engaging position, and stops for limiting the rotary movement of the barrel.

5. The combination, with a sector and a lever movable relatively thereto, of a casing mounted on said lever, said casing having a guideway and a cylindrical bore, at right angles to and intersecting each other, a sector-engaging member mounted in the 50 said guideway, means tending to hold the member out of engagement with the sector, a lock barrel rotatably mounted in said bore and having a portion thereof provided with a notch or recess for the adjacent surface of the said member and said member

having a cylindrical recess in the portion thereof which is presented toward the barrel and which is adapted to receive the said barrel to thereby lock the said member in sector-engaging position, a spring adapted 70 to rotate the barrel when the notch or recess in the member is in register with the cylindrical bore, means for locking the barrel in member engaging position, and stops for limiting the rotary movement of the 75 barrel.

6. The combination, with a sector and a lever movable relatively thereto, of a sector-engaging device slidably mounted on the lever, a spring tending to hold said device out of engagement with the sector, said device comprising a bolt having a cylindrical notch therein, a lock comprising a rotary barrel having a notch or recess in one face thereof and extending transversely with respect to the bolt, means for automatically rotating the said barrel when the notch in the bolt is brought into register therewith, and means whereby said barrel may be rotated to bring its notch into register with 90 the bolt.

7. The combination, with a sector and a lever movable relatively thereto, of a casing mounted on said lever and having a bore extending longitudinally with respect to the 95 lever and a bore at right angles to and intersecting the first mentioned bore, a bolt slidably mounted in the first mentioned bore, said bolt having an extension adapted to engage the sector, a spring tending to move 100 the bolt out of sector-engaging position, said bolt having a cylindrical notch in one wall thereof, means preventing the turning of the bolt in its bore, a rotary barrel in the second bore having a notch in one surface 105 thereof through which the adjacent surface of the bolt may pass, a spring adapted to rotate the barrel when the notch in the bolt is brought into register with its bore, and key operated means for rotating the said 110 barrel in opposition to said spring.

8. The combination, with a sector and a lever movable relatively thereto, of a casing mounted on said lever and having a bore extending longitudinally with respect to the 115 lever and a bore at right angles to and intersecting the first mentioned bore, a bolt slidably mounted in the first mentioned bore, and having an extension adapted to engage the sector, a spring tending to move 120 the bolt out of sector-engaging position, said bolt having a cylindrical notch in one wall thereof, a rotary barrel in the second bore having a notch in one surface thereof 125 through which the adjacent surface of the bolt may pass, a spring adapted to rotate the barrel, when the notch in the bolt is brought in register with its bore, and means for rotating the said barrel in opposition to said spring.

9. The combination, with a sector having a projection and a lever movable relatively to said sector and having a handle, of a, casing mounted on said lever, a bolt slidably mounted in said casing and having hand operating means adjacent to the lever handle, said bolt having at the end adjacent the sector a device which is adapted to engage the sector slots and prevent movement of the lever, means normally holding the bolt in an intermediate position whereby the sector-engaging device is above the body of the sector and below the projection, means carried by the casing and adapted to automatically engage the bolt to lock the said device in sector engaging position, and means for releasing said lock.
10. The combination, with a sector having a projection and a lever movable relatively to said sector, of a sector-engaging device slidably mounted on the lever, means normally supporting said device out of engagement with the body of the sector but in position to engage the projection, means for automatically locking the said device in engagement with the sector, and means whereby the sector-engaging device may be moved away from said projection.
11. The combination, with a sector having a projection and a lever movable relatively thereto, of a locking device slidably mounted on the lever, means yieldingly supporting said device in an intermediate position whereby it is held out of engagement with the body of the sector but is in position to engage said projection, means for automatically locking the said device when moved into sector-engaging position, and means for releasing the lock.
12. The combination, with a sector having a projection and a lever movable relatively to said sector, of a sector-engaging device slidably mounted on the lever, said device comprising a bolt, a guide through which said bolt extends, springs surrounding the bolt on opposite sides of the guide and yieldingly supporting said device out of engagement with the body of the sector but in position to engage the projection, and means for automatically locking the said device in engagement with the sector.
13. The combination, with a sector and a lever movable relatively thereto, of a locking device adapted to engage the sector to prevent movement of the lever with respect thereto, said locking device comprising a bolt having a cylindrical notch therein, a rotary barrel intersecting the path of movement of the bolt and having a notch in the cylindrical body thereof permitting the movement of the bolt, a spring for rotating said barrel when the bolt notch is in register therewith, and a key adapted to be inserted in the barrel to rotate the same into unlocking position, the bolt being provided with a notch for, and permitting the removal of, the key.
14. The combination, with a sector and a lever movable relatively thereto, of a locking device adapted to engage the sector to prevent movement of the lever with respect thereto, said locking device comprising a bolt having a notch therein, a casing having intersecting bores in one of which the bolt is guided, a rotary barrel in the other bore having a notch in the body thereof permitting the movement of the bolt in its bore, means for rotating said barrel when the bolt notch is in register therewith, and a key adapted to be inserted in the barrel to rotate the same in unlocking position, the bolt being provided with a notch for, and permitting the removal of, the key.
15. The combination, with a sector and a lever member movable relatively thereto, of a locking member slidably mounted on the lever and having a portion adapted to engage the sector, means tending to move said member out of engagement with the sector, a rotary cylindrical barrel mounted in one of said members and having a notch in one surface thereof adapted to receive a portion of the other member and permit movement of one member past the other, said other member having a cylindrical notch adapted to receive the cylindrical body of said barrel when said locking portion is moved to sector engaging position, and means whereby the barrel may be rotated.

In testimony whereof, I hereunto affix my 100
signature in the presence of two witnesses.

CHESTER E. CLEMENS.
